Specification for Design.

Patented July 28, 1914.

Application filed May 11, 1914. Serial No. 837,953. Term of patent 3½ years.

To all whom it may concern:

Be it known that we, JOHN SCHNEIDER and HENRY SCHNEIDER, citizens of the United States, residing at Ann Arbor, in the county of Washtenaw and State of Michigan, have invented a new, original, and ornamental Design for a Cowl-Dash for Automobiles, of which the following is a specification, reference being had to the accompanying drawing, forming a part thereof.

Figure 1 is a perspective view looking at

the dash from the front. Fig. 2 is a perspective view looking at the dash from the rear. Fig. 3 is a side elevation.

The figures illustrate our new design.

What we claim is:

The ornamental design for a cowl dash for automobiles substantially as shown.

JOHN SCHNEIDER.

HENRY SCHNEIDER.
